(57) **CLAIM**

The ornamental design for a climate sensor, as shown and described.

DESCRIPTION

FIG. 1 is an upper front perspective view of the novel climate sensor.

FIG. 2 is a lower front perspective view of the sensor of FIG. 1.

FIG. 3 is an upper rear perspective view of the novel sensor of FIG. 1.

FIG. 4 is a lower rear perspective view of the novel sensor of FIG. 1.

FIG. 5 is a front side view of the sensor of FIG. 1.

FIG. 6 is a rear side view of the sensor of FIG. 1.

FIG. 7 is a right side view of the sensor of FIG. 1.

FIG. 8 is a left side view of the sensor of FIG. 1.

FIG. 9 is a top view of the sensor of FIG. 1; and,

FIG. 10 is a bottom view of the sensor of FIG. 1.
